(57) **CLAIM**

The ornamental design for a ceiling fan, as shown and described.

DESCRIPTION

FIG. 1 is a top perspective view of a ceiling fan showing my new design;

FIG. 2 is a bottom perspective view of the ceiling fan of FIG. 1;

FIG. 3 is a front view of the ceiling fan of FIG. 1;

FIG. 4 is a rear view of the ceiling fan of FIG. 1;

FIG. 5 is a right side view of the ceiling fan of FIG. 1;

FIG. 6 is a left side view of the ceiling fan of FIG. 1;

FIG. 7 is a top view of the ceiling fan of FIG. 1; and,

FIG. 8 is a bottom view of the ceiling fan of FIG. 1.

Portions of the ceiling fan shown in broken lines, including the grid pattern at the root end of the blades, form no part of the claimed design.

The ceiling fan blades are shown with a symbolic break in their length. The appearance of any portion of the ceiling fan blades between the break lines forms no part of the claimed design.
